UNITED STATES PATENT OFFICE

WILBUR H. ARMACOST, OF NEW YORK, N. Y., ASSIGNOR TO THE SUPERHEATER COMPANY, OF NEW YORK, N. Y.

BOILER

Application filed April 17, 1928. Serial No. 270,664.

This invention relates to water-tube boilers equipped with steam superheaters. It is correct theoretically, and has been found expedient in practice, to locate the steam superheater in a position such that the gases from the furnace come into contact with the superheating surface after they have passed over sufficient boiler surface to remove enough of the heat so that the superheater will not be endangered, but to keep the superheater as close to the furnace as is consistent with this protective idea. In ordinary boiler operation the output of the boiler will be variable but the location just described results in a substantially constant final temperature of the steam leaving the superheater even under great load variations. Superheaters placed at a point more remote from the furnace do not obtain such temperature uniformity.

In boilers of the so-called horizontal water-tube type, it has become quite customary to locate the superheater in what is called the "interdeck" position to obtain the advantages mentioned above. The boiler is, in other words, subdivided into two banks, a lower and an upper, the superheater being located between them. The lower bank is made relatively small in size, consisting of three to five rows of tubes which are exposed to the furnace gases and furnace radiation throughout their entire length. The upper bank is usually baffled to give three passes to the gases. The superheater is placed in the first of these passes in the free space between the two banks, or it is distributed throughout the free space between the two banks from front to rear of the boiler.

This general arrangement is good except for the fact that it results in a considerable amount of waste space within the boiler, making the setting for the entire boiler unnecessarily large and expensive. Other types of boilers, such as the Sterling type, are even more objectionable on this score.

It is the object of the present invention to provide a boiler with an ideal space for the superheater, the boiler itself being so arranged that there is substantially no space

wasted within the housing but that every cubic foot of the space is usefully occupied.

A further object is to provide a boiler in which there shall be vigorous circulation of the water.

Other and more detailed objects will appear from the following description.

The invention is illustrated in the three drawings filed herewith, in which Fig. 1 is a longitudinal vertical section through a boiler of my design, Fig. 2 is a similar view of a somewhat modified form of the invention, and Fig. 3 is a similar view of a further modification.

Referring first to the form illustrated in Fig. 1, the furnace is shown at 1, the boiler proper being located above the furnace. The walls of the furnace 1 are surrounded on all sides by water screens. At the front, for example, the water tubes 2 and 3 connected to lower and upper headers 4 and 5 screen the wall 6 against the intense radiant heat of the furnace. Rear wall 7 is similarly screened by water tubes 8 and connected to lower and upper drums 9 and 10. The sides of the furnace will in practice be similarly screened, although this is not shown in the drawings. Lower drum 9 is connected to lower front drum 4 by means of the water tubes 11.

This furnace is designed to be heated by burners 12 which use pulverized liquid or gaseous fuel. My invention, however, is not limited in this respect, and a furnace using solid fuel and equipped for this purpose with the proper grate may be substituted.

The boiler proper is enclosed in the housing 13. Against the front and rear walls of this housing are arranged the headers 14 and 15 which are preferably sectional but may be of the so-called box header type if desired. A bank of tubes 16 extending at the usual angle from front to back and comprising the proper number of rows of tubes connects these two headers. The exact number of rows may vary from case to case, depending upon circumstances. While the bank is somewhat inclined to the horizontal, the usual practice of calling it a horizontal bank will be followed hereinafter.

Located about centrally above the bank 16

and at some distance above it is the drum 17. This is connected to the upper portion of headers 15 by the bank of tubes 18. The lower portions 19 of these tubes are straight, 5 and parallel to the tubes 16 and are connected by bends to the vertical straight portions 20. The upper ends are bent toward and connected to the drum 17.

Front headers 14 extend vertically some 10 distance above the bank of tubes 16 and their upper ends are connected to drum 17 by the circulators 21. The tubes making up the water screen 3 have their upper ends connected to the lower ends of the headers 14.

15 The upper header 10 of the water screen 8 is connected at one or both ends by means of the riser or risers 22 and the pipes 23 to the drum 17. These risers 22 and pipes 23 preferably lie laterally entirely outside of the 20 outline of the boiler, the drum 17 being extended beyond the setting at one or both ends, as required.

On the top of the bank of tubes 16 a horizontal baffle 24 extends from the rear headers 15 forward, stopping at the point 25 some distance from the front headers, from which point a vertical baffle 26 extends upward adjacent to the front of the tubes 18.

30 A vertical baffle 27 between baffle 26 and the rear wall of the housing extends from a point some distance above the baffle 24 upward. A short baffle 28 closes the space between this baffle and the drum 17.

The entire space between the front headers 14 and the baffle 26 is occupied by the 35 superheater 29. This superheater comprises vertically arranged tubular loops connected to the two headers 30 and 31 lying outside of the setting of which 31 is connected by pipe 40 32 to the steam drum 17 and of which 30 delivers the superheated steam to the steam main (not shown). The straight portions of 45 the tubular units connecting the looped structures to the headers extend through between the circulators 21. In the upper portion of the last pass is located the economizer 33.

Between the lowermost of the tubes 18 and the baffle 24 there is left just sufficient space for a soot pocket.

50 At the lower ends of the rear headers 15 is the sludge chamber 34 connected to the lower ends of the headers 15 by the connectors 35. Sludge is periodically blown off from this chamber in the usual manner.

55 The lower rear headers 9 are connected to the steam drum 17 at one or both sides by the downcomer or downcomers 36.

The form of the invention shown in Fig. 2 is substantially like that of Fig. 1, the principal difference residing in the baffling of the 60 curved bank of tubes. The rear bank of tubes is divided into two portions separated by a space 37, and the baffle 27 instead of crossing the tubes lies entirely on the uppermost row of tubes 38 of the first portion of

the bank. Convenient access is thus furnished for the maintenance of this baffle. A man can enter through the hole 39 and inspect and repair the baffle. Preferably two additional rows of tiles 40—40 extend from the baffle 27 to the rear bank in order to direct the gases out of the space 37 into the rear portion of the bank.

The baffle 26 is in this form shown as lying between the vertical portions of the two first 75 rows of tubes of the upper bank.

In the form of the invention according to Fig. 3, the rear header 15 does not extend up far enough to have the lower ends of the upper bank 18 secured to it. Instead, a lower drum 41 is used, parallel to the upper drum 17 and adjacent to the header 15, to which it is connected by nipples 42. The tubes of the bank 18 are given the more conventional shape in this case of tubes extending between 80 drums, although this is not essential. With the shape shown for these tubes the superheater space becomes more nearly triangular, and it will be found more convenient to give the superheater elements 29a the shape shown 85 in the drawing and to have the headers 30a and 31a in front of the front wall of the setting.

It will be seen that the boiler provided by my invention has substantially every available cubic foot within the setting occupied by heat absorbing surfaces. By having the upper bank of tubes extend forward and upward and locating the drum 17 at a considerable height above the lowest point of the 95 boiler, the difference in hydrostatic head of the portions of the boiler containing the heated water mixed with steam and the portion containing the water flowing downward from the drum is emphasized and the circulation within the boiler greatly promoted.

I claim:

1. In apparatus of the class described, the combination of vertical front and rear headers, a bank of horizontal water tubes connecting them, a transverse steam and water drum some distance above the bank and approximately midway between the headers, a second bank of water tubes connected to one of the headers and extending toward the other header to a point under the drum and then upward toward the drum, a connection from the second header to the drum, a superheater in the angular space formed by the two banks, a housing enclosing the boiler and superheater, and a connection from the drum to the superheater.

2. In apparatus of the class described, the combination of vertical front and rear headers, a bank of horizontal water tubes connecting them, a transverse steam and water drum some distance above the bank and approximately midway between the headers, a second bank of water tubes connected to the rear header and to the drum, the tubes of 120

said second bank comprising straight lengths parallel to the first bank and vertical straight lengths, a baffle comprising a portion extending above the first bank from the rear header 5 to a point short of the front header and a vertical portion along the second bank and terminating short of the drum, a superheater above the first bank and forward of the vertical portion of the baffle, a housing enclosing the boiler and superheater, a connection from the front header to the drum, and a connection from the drum to the superheater.

3. In apparatus of the class described, the 15 combination of a boiler housing, a bank of substantially horizontal, straight water tubes extending from front to back of the housing, a bank of curved water tubes above the first named bank distributed through the space 20 from the rear wall to a point spaced from the front wall, said curved tubes having portions generally parallel to the first bank, and generally vertical portions, and a superheater comprising tubular elements distributed 25 through the space between said point and the front wall, a steam and water drum to which one end of all the tubes and the superheater are connected, and means interconnecting all the water tubes at their other 30 ends.

4. In apparatus of the class described, the combination of a boiler housing, a bank of substantially horizontal, straight water tubes extending from front to back of the housing, 35 a bank of curved water tubes above the first named bank distributed through the space from the rear wall to a point spaced from the front wall, said curved water tubes having portions generally parallel to the first 40 bank and generally vertical portions, said horizontal portions of the lowermost of the curved tubes being spaced only a small distance from the horizontal bank, and a superheater comprising tubular elements distributed 45 through the space between said point and the front wall, whereby the entire space between the front and back of the housing is occupied by heat absorbing surfaces, a steam and water drum to which one end of all the 50 water tubes and the superheater are connected, and means interconnecting all the water tubes at their other ends.

5. In apparatus of the class described, the combination of a housing enclosing a generally rectangular space, a horizontal bank 55 of tubes distributed uniformly through the lower portion of said space, a curved bank of tubes with generally horizontal portions and vertical portions distributed uniformly 60 through the space above the horizontal bank to a point intermediate between the front and rear walls, header means interconnecting the ends of the horizontal portions of the curved bank and one set of ends of the horizontal 65 bank of tubes, a drum with which the other

ends of all the tubes communicate, and a superheater distributed uniformly through the remaining portion of the space above the horizontal bank, said superheater being connected to said drum. 70

6. In apparatus of the class described, the combination of a boiler housing having front, rear, and side walls, a baffle extending from the rear wall forward to a point spaced from the front wall, a baffle extending upward from this point, a bank of substantially horizontal water tubes below the horizontal baffle and extending from front to rear of the housing, other water tubes arranged within the angle formed by the two baffles and extending from the rear wall forward and upward, header means interconnecting the rear ends of all the tubes, a steam and water drum with which the other ends of all of the tubes communicate, and a superheater arranged in the space between the upwardly extending baffle and the front wall, said superheater being connected to said drum. 80 85

7. In apparatus of the class described, the combination of a boiler housing having front, rear and side walls, a steam and water drum at the top of the housing, water containing means adjacent to the rear wall below the drum, water tubes connecting the water containing means and the drum, said tubes being distributed throughout the space from side to side and from the back to a point spaced from the front wall, whereby a space is left extending from side to side and from the front to said point, header means adjacent to the front wall and above said water containing means, a bank of water tubes connecting said header means and said water containing means and distributed from side to side, connections to the drum from said header means, and a superheater distributed throughout said space above said bank of water tubes and connected to the header. 90 95 100 105
